(57) **CLAIM**

The ornamental design for a bubble bottle and bubble wand, as shown and described.

DESCRIPTION

FIGS. 1–6 illustrate the invention in its closed state in which:

FIG. 1 is a front view;

FIG. 2 is a first side view;

FIG. 3 is a top plan view;

FIG. 4 is a rear end view;

FIG. 5 is a second side view;

FIG. 6 is a bottom view;

FIGS. 7–9 illustrate the invention in its open state in which:

FIG. 7 is an exploded front view;

FIG. 8 is an exploded side view; and,

FIG. 9 is a top plan view of the bubble bottle only.
